UNITED STATES PATENT OFFICE.

HENRY R. GOGAY AND THOMAS F. BERRILL, OF COLUMBUS, OHIO, ASSIGNEES TO SOLAR METAL PRODUCTS COMPANY, INC., OF NEW YORK, N. Y., A CORPORATION OF NEW YORK.

CONSTRUCTION OF METAL DOORS.

1,281,941.

Specification of Letters Patent. Patented Oct. 15, 1918.

Application filed January 6, 1916. Serial No. 70,658.

To all whom it may concern:

Be it known that we, HENRY R. GOGAY and THOMAS F. BERRILL, citizens of the United States, and residents of Columbus, 5 in the county of Franklin and State of Ohio, have invented a new and useful Improvement in the Construction of Metal Doors, of which the following is a specification.

This invention relates to an improvement 10 in the construction of metal doors, with the object in view of providing a hollow fire-proof door which will be rigid, light and durable.

A further object is to provide a metal door 15 which is readily assembled and cheap to manufacture.

A still further object is to provide certain improvements in the form, construction and arrangement of the several parts whereby 20 the above mentioned and other objects may be effectively carried out.

A practical embodiment of our invention is represented in the accompanying drawings, in which—

25 Figure 1 represents a front elevation of the upper corner of a metal door, with the panel therein, a portion of which door is broken away to show the parts more clearly below,

30 Fig. 2 represents a vertical section taken in the plane of the line A—A of Fig. 1

Fig. 3 represents a detail horizontal section taken in the plane of the line B—B of Fig. 1,

35 Fig. 4 represents a detail horizontal section taken in the plane of the line C—C of Fig. 1,

40 Fig. 5 represents a detail vertical section similar to Fig. 2, illustrating a modified form of panel molding, and

Fig. 6 represents a detail section of a form of panel molding having a strip removably secured thereto.

In the drawings, we have shown only a 45 portion of a door, of which the two stiles are denoted by 1 and the top rail by 2.

It will be understood that the other rails, not shown, which are used in the building of a door, will be constructed similar to the 50 top rail.

The stile 1 is of U-shaped construction and provided along its inner vertical edges with lateral grooves 3.

The rail 2 comprises two plates 4 having

lateral grooves 5 along their inner horizontal edges, oppositely disposed, and laterally turned, vertical tongues 6 along their ends located in the vertical grooves 3 of the stiles 1.

A molding 7 is secured between the stiles 60 and rails by having its free edges 8 located in the grooves 3 of the stiles and grooves 5 of the rail. This molding 7 is also provided with a recess 9 for the reception of a panel 10.

65 Spacing bars 11 and 12 are secured within the stiles and rails at their grooved inner vertical and horizontal edges, respectively. These spacing bars are provided with longitudinal recesses 13 for receiving the walls of 70 the panel recess 9.

The spacing bars 11 are arranged with the side walls adjacent to the inner walls of the stiles 1 and the spacing bars 12 are arranged with the side walls adjacent to the inner 75 walls of the rails 2, thereby forming convenient posts for the welding operation.

Thus it will be seen that the spacing bars 11 and 12, being located between the inner walls of the stiles and rails at their grooved 80 inner vertical and horizontal edges, and the panel and molding coacting with recesses 13 in the bars, tend to strengthen the door at this point.

The upper edge of the door is sealed by 85 means of a channel bar 14 which rests upon the vertical tongues and grooves of the rails and stiles, cut away at 15 for that purpose, so that the side walls of the channel bar will be in close contact with the inner walls of 90 the stiles and rails for welding.

The lower edge of the door (not shown), may also be sealed in a similar manner.

In the form shown in Fig. 5 the panel is provided with exterior surface plates 16 95 having an asbestos lining 17 interposed therein. In this form, the construction of the molding 7 is made with a recess 18 suitable for the reception of the lined panel.

In Fig. 6, we have shown a modified form 100 of panel molding in which a strip 19 is removably secured to the molding by means of a screw 20 having a threaded engagement with a plate 21 secured to the molding.

It is obvious that various changes may be 105 resorted to in the form, construction and arrangement of the several parts without departing from the spirit and scope of our in-

vention; hence we do not wish to limit ourselves strictly to the structure herein set forth, but

What we claim is:

- 5 1. In a sheet metal door, a stile having oppositely disposed lateral grooves along its inner vertical edges, a vertical spacing bar located within the stile adjacent to said grooves and having a longitudinal recess and in said stiles and rails adjacent to said grooves and having longitudinal recesses and a panel molding provided with inwardly turned edges located in said grooves and a panel recess interposed between said edges, the walls of said recess being in position to coact with the longitudinal recesses of said spacing bars for stiffening the molding. 35
- 10 2. In a sheet metal door, stiles and rails having laterally disposed grooves along their vertical and horizontal inner edges respectively, said rails having laterally turned tongues along their ends located in said vertical grooves in the stiles, spacing bars located within said stiles and rails adjacent to said grooves and having longitudinal recesses and a panel molding provided with inwardly turned edges located in said grooves and a panel recess interposed between said edges, the walls of said recess being in position to coact with the longitudinal recesses of said spacing bar for stiffening the molding. 40 45
- 15 3. In a sheet metal door, a rail having oppositely disposed lateral grooves along its inner horizontal edges, a horizontal spacing bar located within the rail adjacent to said grooves and having a longitudinal recess and a panel molding provided with inwardly turned edges located in said grooves and a panel recess interposed between said edges, the walls of said recess being in position to coact with the recess in the spacing bar for stiffening the molding. 50
- 20 4. In a sheet metal door, stiles and rails having oppositely disposed lateral grooves along their vertical and horizontal inner edges respectively, said rails having laterally turned tongues along their ends located in said vertical grooves in the stiles, spacing bars located within said stiles and rails adjacent to said grooves and having longitudinal recesses and a panel molding provided with inwardly turned edges located in said grooves and a panel recess interposed between said edges, the walls of said recess being in position to coact with the longitudinal recesses of said spacing bar for stiffening the molding. 55
